UNITED STATES PATENT OFFICE.

RALPH WARNER, OF WATERTOWN, MASSACHUSETTS.

PAIL OR LIKE RECEPTACLE.

SPECIFICATION forming part of Letters Patent No. 417,299, dated December 17, 1889.

Application filed September 30, 1889. Serial No. 325,496. (No model.)

To all whom it may concern:

Be it known that I, RALPH WARNER, a citizen of the United States, residing at Watertown, in the county of Middlesex and Commonwealth of Massachusetts, have invented certain new and useful Improvements in Pails and like Receptacles, of which the following is a full specification, reference being made to the accompanying drawings, forming a part thereof, of which—

Figure 1 is a sectional elevation of a pail embodying my invention, and Fig. 2 is an enlarged sectional detail view showing the hoop in place.

My invention consists of certain new and useful improvements, as hereinafter set forth, in the construction of pails, tubs, churns, barrels, covered buckets, kegs, and similar receptacles. These articles as ordinarily constructed, when made of wooden strips or staves, are bound together by hoops or bands around the outside thereof. When thus constructed, they are subject to the disadvantage of easily falling to pieces when the wood

shrinks and the hoops drop off—a very common occurrence in receptacles of this class, especially with pails when allowed to become dry.

I will proceed for convenience to describe my invention as applied to the ordinary water-pail, calling attention to the fact that the same construction is equally applicable to all the above-named articles and many others.

A is the body of the pail, preferably constructed in the usual manner of wooden strips 35 tongued and grooved together, but which may be made of any desired material. Along the top and bottom edges of the pail are made grooves $b b'$, preferably cut around the body thereof when the pail is still in the lathe, and 40 into these grooves $b b'$ are pressed hoops $B B'$, respectively, which, when in position, are wholly contained within the body of the pail. I preferably make the grooves $b b'$ inclined at an angle such that when the hoops are pressed

therein the strips of which the pail-body is 45 composed are tightly and firmly drawn together. Instead of hoops consisting of bands, as herein shown, wire hoops or rings may, if desired, be employed, in which case the grooves $b b'$ need not be made so deep. 50

When the hoops are once in position, the portions of the grooves and hoops exposed to view are preferably covered with putty c or any other suitable filling material, (see Fig. 2,) thereby entirely concealing the hoops from 55 view, and serving, moreover, to more effectually hold the hoop firmly in the groove. The hoops being wholly contained within the material forming the body of the pail, the pail presents a perfectly smooth neat appearance, 60 and is at the same time much stronger than the ordinary hooped pail in that the material cannot by any possibility shrink away from the hoop, nor can the hoop get out of place in any way. A pail thus constructed, while much 65 stronger and neater in appearance, costs no more than the ordinary pail with hoops on the outside.

I claim—

1. A pail or other receptacle provided along 70 the top and bottom edges with grooves, in combination with hoops or rings concealed within said grooves, substantially as and for the purposes described.

2. A pail or other receptacle provided along 75 its top and bottom edges with inclined grooves, in combination with hoops fitting said grooves, whereby when the hoops are pressed in place the material of the pail-body is drawn firmly together and the hoops are concealed, sub- 80 stantially as described.

In witness whereof I have hereunto set my hand.

RALPH WARNER.
